UNITED STATES PATENT OFFICE.

SYDNEY BUCKLEY, OF PHILADELPHIA, PENNSYLVANIA, ASSIGNOR TO NILES-BEMENT-POND COMPANY, OF NEW YORK, N. Y., A CORPORATION OF NEW JERSEY.

BRIDGE FOR TRAVELING CRANES.

1,296,759.

Specification of Letters Patent. Patented Mar. 11, 1919.

Application filed June 2, 1917, Serial No. 172,426. Renewed January 7, 1919. Serial No. 270,061.

To all whom it may concern:

Be it known that I, SYDNEY BUCKLEY, a citizen of the United States, and a resident of Philadelphia, in the county of Philadelphia and State of Pennsylvania, have invented certain new and useful Improvements in Bridges for Traveling Cranes, of which the following is a specification, reference being had therein to the accompanying drawings.

The invention relates more particularly to traveling cranes of the class in which each comprises a movable bridge having two parallel separated elements respectively carrying rails. A hoisting mechanism is provided which consists of a trolley movable along the rails on the bridge and depending load engaging elements which usually extend between the two elements of the bridge.

The invention relates especially to the bridge elements of cranes of the type specified, and a construction embodying my present invention is in some respects similar to the construction disclosed and claimed in my copending application for cranes, Serial No. 149,180, filed February 17, 1917. In the design of cranes, in order to meet the various and different requirements as concerns span, capacity, character of load, operating conditions, etc., it is necessary to vary the character of the bridge construction. The object of the present invention is to provide a bridge construction of the general type set forth in my aforesaid copending application but which is adapted to meet different requirements.

In the accompanying drawings I have illustrated the embodiment of the invention which I now deem preferable, but it will be understood that the construction shown is intended to be merely illustrative and is not intended to define or limit the scope of the invention. Particularly it will be understood that the forms of the girders, the shapes of the structural sections used, the means for connecting the several girders together and the various structural details can be varied widely in accordance with the requirements of any particular case or in accordance with the preferences of the designer.

Of the drawings:

Figure 1 is a side elevation of a crane

embodimenting the invention, some of the parts to which the invention does not directly relate being omitted.

Fig. 2 is a transverse vertical sectional view, the part at the left being taken along the line 2-2 of Fig. 3 and the part at the right being taken along the line 2A-2A of Fig. 3.

Fig. 3 is a longitudinal vertical sectional view taken along the center line of one of the bridge elements.

Fig. 4 is a fragmentary plan view of one of the bridge elements.

Referring to the drawings, particularly to Figs. 1 and 2, it will be observed that I have shown a crane comprising a traveling bridge which is carried at its ends on trucks 70 which travel along rails 1, 1 supported on suitable elevated structures 2, 2. The bridge is made up of two longitudinal elements arranged with a space between them. The two elements are connected at the ends by 75 suitable transverse members 3 as shown in Fig. 2. Preferably there is provided a separate two-wheeled truck element 4 for each end of each bridge element.

For the purpose of moving the crane as 80 a whole along the rails 1, 1, one or more truck wheels at each end of the bridge are connected with a suitable driving motor. As illustrated, one of the truck wheels at each end is connected with a gear wheel 5 85 which meshes with a pinion 6 on a shaft 7 which extends longitudinally from one end of the bridge to the other. A motor 8 is provided for rotating the shaft 7, thus serving to move the bridge in one direction or 90 the other as required.

Supported on each of the said longitudinal bridge elements is a rail 9. A suitable trolley or hoisting mechanism is provided which is supported on the rails 9, 9, and 95 is adapted to travel along them. The hoisting mechanism as a whole is represented in the drawings by 10, but as this hoisting mechanism of itself constitutes no part of the present invention, detailed description 100 thereof can be omitted. It is sufficient to point out that the hoisting mechanism is provided with a suitable load-engaging device such as the hook 11 which is suspended by a cable or cables 12, passing through 105 the space between the two longitudinal ele-

ments of the bridge. By means of a motor 13 the rope can be wound upon or unwound from a drum 14, thus causing the hook with its load to be raised or lowered.

5 There is a suitable cage 15 which is provided with space for an operator and with suitable controlling devices whereby the movements of the bridge and of the hoisting mechanism can be started, stopped and controlled as required.

10 The present invention relates primarily to the construction of the two main side elements of the bridge, and as these elements are similar to each other it will be sufficient 15 to describe but one of them in detail. In the drawings many of the structural details are omitted or are incompletely shown, as these constitute no part of the invention and can be varied as desired.

20 In the construction presented in my aforesaid application Serial No. 149,180, each side element of the bridge comprises two separated main girders and a supplemental rail-carrying girder located between the main 25 girders. In the said construction the load is transmitted from the central rail-carrying girder to the upper longitudinal elements of the main girders by means of transverse connecting members in the form of beams. The 30 present construction differs primarily from the aforesaid construction in the provision of strut members for transmitting the load from the rail-carrying girder to the lower longitudinal members of the main girders.

35 As illustrated, each side element of the bridge comprises two main girders 16 and 17 between which there is positioned a longitudinal rail-carrying girder 18. I do not limit myself as to the exact forms of these 40 girders, but under most circumstances I prefer to provide a rail-carrying girder which is a simple rolled section such as an I-beam, and to provide main girders which are built up of separate rolled metal parts forming 45 upper and lower compression and tension members and diagonal truss members.

50 In the construction shown, the upper longitudinal member of each girder comprises angle bars 19 and 20 and a plate 21 between the bars. Similarly the lower longitudinal member of each girder comprises two angle bars 22 and 23 and a plate 24 between the bars. The upper and lower longitudinal members are connected by diagonal truss 55 members 25 and 26 which are shown as being in the form of angle bars. The longitudinal

members of the main girders are connected at their ends to suitable end structures 27, 27.

The two girders are connected together and spaced by means of suitable transverse 60 members such as the angle bars 28, 28 at the top and 29, 29 at the bottom. There are also provided diagonal braces 30 and 31 at the top and 32 and 33 at the bottom.

65 For supporting the rail-carrying girder or beam 18 I provide a plurality of diagonal struts 34 and 35 arranged in pairs, the struts of each pair engaging the beam 18 at the top and at the bottom respectively engaging the longitudinal members of the main girders 16 and 17. Preferably I provide a pair of struts at each plane where two diagonal members 26 and 25 join the lower longitudinal members. Preferably I also provide other pairs of struts at the planes where the diagonal members 25 and 26 join the upper longitudinal members. In order that the lower longitudinal members may be properly supported at the latter planes, I provide vertical members 36 which extend from the upper longitudinal members down to the lower longitudinal members.

70 It will be seen that by this construction I have provided a simple means for transmitting the load from the rail-carrying girders to the main girders.

75 What I claim is:

80 1. A traveling crane bridge element consisting of two individually complete main 90 girders each comprising an upper longitudinal compression member, a lower longitudinal tension member and diagonal truss members, a rail-carrying girder between the main girders at or near the level of the upper members of the main girder, and 95 means for supporting the rail-carrying girder directly from the lower members of the main girder.

100 2. A traveling crane bridge element consisting of two individually complete main girders each comprising an upper longitudinal compression member, a lower longitudinal tension member and diagonal truss members, a rail-carrying girder between the main girders at or near the level of the upper members of the main girder, and 105 diagonal supports extending to the rail-carrying member from the lower member of each main girder.

110 In testimony whereof, I hereto affix my signature.

SYDNEY BUCKLEY.
